EVAPORATOR

Franklin G. Slagel, Buffalo, N. Y., assignor to
 Fedders Manufacturing Company, Inc., Buffalo,
 N. Y., a Corporation of New York

Application August 13, 1930, Serial No. 475,033
 Renewed January 10, 1933

8 Claims. (Cl. 62—95)

This invention relates to mechanical refrigerating systems and more particularly to evaporators.

An object of my invention is to provide an evaporator unit in which a plurality of tubes are associated to form superposed freezing chambers.

Another object of the invention is to provide an evaporator consisting of a header and associated tubes, there being a main vertical tube from which a plurality of horizontal tubes extend to form superposed freezing chambers.

A further object of my invention is to provide a simple form of evaporator having a plurality of superposed freezing chambers formed by an association of tubes and fins.

Other objects of the invention will appear from the following description taken in connection with the drawing, which forms a part of the specification, and in which:

Fig. 1 is side elevational view of an evaporator incorporating the invention;

Fig. 2 is an end elevational view of the same;

Fig. 3 is a view looking at the bottom of the evaporator;

Fig. 4 is a fragmentary view looking at the bottom of evaporator, in which the bottom loops are of a modified form.

Referring now to the drawing by characters of reference, the header shown is comprised of a cylindrical sheet metal shell 10 having an open end closed by the plate 11. An outlet tube 12 projects into the header from the end plate and communicates with a union 13 which is secured to the plate by cap screws 14, the union being connected with the compressor (not shown) of an evaporator—compressor—condenser refrigerating system. Another union 15 is secured to the end plate by cap screws 16, and in communication with an inlet passage 17 extending through the end plate. The union 15 is connected with a condenser (not shown), and a needle valve 18 is arranged to cooperate with a seat to control the flow of liquid refrigerant into the header. The needle valve is reciprocated in the passage by an open float 19 which is pivoted at 20 to the end plate. As the liquid refrigerant in the header vaporizes it is sucked out through the tube 12, which extends into the float, and the float moves with the level of the liquid refrigerant body so that as it falls the float moves the valve to permit liquid refrigerant through the inlet passage until a predetermined body is present in the header, whereupon the valve is seated.

In order to increase the heat transfer area of the evaporator surface and to provide for freez-

ing liquids, I associate tubes and fins with the header. A tube loop 21 depends from the rear end of the header, and the open ends thereof are arranged in open communication with the liquid refrigerant in the header so that the tube is filled with refrigerant. The header, preferably, extends in a horizontal plane, while the tube loop depends vertically therefrom. A series of superposed parallel tubes 22 extend horizontally below the header, and their ends are secured one to each leg 23 of the loop 21 and in open communication with the refrigerant therein. Each of the tubes 22 are bent centrally in a reverse direction to form an inner loop 24 so that a shelf having high thermal efficiency is thereby formed.

The space between the header and the upper tube 22, and the spaces between the adjacent tubes 22 provide freezing chambers, each of which is substantially enclosed by sleeves 25 open at one end for the insertion of pans (not shown). In order to lend rigidity to the tube structure and to increase the thermal efficiency of the evaporator, I provide vertically extending fin members 26 which are fixed, by soldering or otherwise, to the sides of the tubes 22 and the header. The sleeves are in intimate contact with the fins, the tubes 22 and the tube 21, so that quick freezing within the sleeves will result.

In Fig. 4 I have illustrated a modified form of horizontal tubing, and in this instance a pair of loops 30 are utilized instead of the single tubing 22. The open ends of each pair of loops are secured to one or the other legs of the tube 21 and in open communication with the refrigerant therein.

It will be seen that the header and tube arrangement described provides a simple multiple chamber quick freezing device which serves also to absorb heat from the air or other medium passing thereby.

Although this invention has been described in connection with certain specific embodiments the principles involved are susceptible of numerous other applications which will readily occur to persons skilled in the art, and the invention is therefore to be limited only as indicated by the scope of the appended claims.

What I claim is:

1. In an evaporator for refrigerating systems, a header adapted to contain a body of liquid refrigerant, means for admitting refrigerant into the header to maintain the liquid body substantially constant, a tube depending from the header including legs having their open ends in open communication with the liquid body, and a plu-

- rality of parallel tubes in planes beneath the header, said tubes extending laterally from said depending tube and having their ends connected in open communication with the interior of the 5 legs of the depending tube.
2. In an evaporator for refrigerating systems, a header, means for admitting refrigerant to maintain a body of liquid refrigerant in the header, a tube loop depending from one end of the 10 header and secured thereto with its ends in open communication with the liquid body, and a plurality of parallel tubes arranged in planes beneath the header, said tubes extending laterally from said depending tube and having their ends 15 connected in open communication with the interior of the legs of the tube loop.
3. In an evaporator for refrigerating systems, a header, means for admitting refrigerant to maintain a body of liquid refrigerant in the 20 header, a tube loop depending from one end of the header and secured thereto with its ends in open communication with the liquid body, a plurality of parallel tubes beneath the header having their open ends connected to the legs of the tube loop and in open communication with the refrigerant 25 therein, and a plurality of vertical fins connected to the sides of the header and the parallel tubes.
4. In an evaporator for refrigerating systems, a horizontally extending header, a tube loop depending from the header and open to the interior thereof, horizontally extending parallel tubes beneath the header and secured in open communication with the legs of the tube loop, said parallel 30 tubes projecting laterally from said depending tube, and means for maintaining a body of liquid refrigerant in the header and tubes.
5. In an evaporator for refrigerating systems, a horizontally extending header, a tube loop depending from one end of the header and open to the bottom interior thereof, horizontally extend- 35
- ing parallel tubes beneath the header secured in open communication with the legs of the tube loop, means for maintaining a body of liquid refrigerant in the header and tubes, and sleeves intermediate the horizontal tubes, said sleeves being in intimate contact with adjacent horizontal tubes. 8
6. In an evaporator for refrigerating systems, a horizontally extending header, a tube loop depending from one end of the header and in open communication with the bottom of the interior thereof, horizontally extending parallel tubes spaced beneath the header and secured with their ends in open communication with the legs of the tube loop, fins secured to the sides of the header and the horizontal tubes, and sleeves intermediate the horizontal tubes, said sleeves being in intimate contact with the tubes and fins. 8
7. In an evaporator for refrigerating systems, a horizontally extending header, a tube loop depending from one end of the header and in open communication with the bottom of the interior thereof, horizontally extending parallel spaced tubes beneath the header and secured with their ends in open communication with the legs of the tube loop, said horizontal tubes having a central portion bent to extend parallel to the end portions, and means for maintaining a body of liquid refrigerant in the header and the tubes. 9
8. In an evaporator for refrigerating systems, a header, a tube loop depending from said header and in open communication therewith, a plurality of superposed tubes arranged in spaced relation and having their ends connected to the tube loop, said tubes extending laterally of the tube loop for forming shelves for ice trays, and means for maintaining liquid refrigerant in the header and tubes. 10
